CLAIM

The ornamental design for a medical heat pad as shown and described.

DESCRIPTION

Fig. 1.1 is a front perspective view of a medical heat pad according to my design,

Fig. 1.2 is a back perspective view thereof,

Fig. 1.3 is a front elevation view thereof,

Fig. 1.4 is a back elevation view thereof,

Fig. 1.5 is a top view thereof,

Fig. 1.6 is a bottom view thereof, and

Fig. 1.7 is a right view thereof.

(Continued)

The broken lines shown in Fig. 1.1-Fig. 1.4 are for the purpose of illustrating portions of the medical heat pad and forms no part of the claimed design.
